US00D921284S

(12) **United States Design Patent** (10) **Patent No.:** **US D921,284 S**
(45) **Date of Patent:** **** Jun. 1, 2021**

(54) **VAPORIZER CARTRIDGE**

- (71) Applicant: **JUUL Labs, Inc.**, San Francisco, CA (US)
- (72) Inventors: **Christopher L. Belisle**, Somerset, WI (US); **Steven Christensen**, Burlingame, CA (US); **Eric Joseph Johnson**, San Francisco, CA (US); **Jason King**, San Francisco, CA (US); **James Monsees**, San Francisco, CA (US); **Matthew Rios**, San Francisco, CA (US); **Bryan White**, Pleasanton, CA (US)
- (73) Assignee: **JUUL Labs, Inc.**, San Francisco, CA (US)

(**) Term: **15 Years**

(21) Appl. No.: **29/725,934**

(22) Filed: **Feb. 27, 2020**

Related U.S. Application Data

(63) Continuation of application No. 29/657,385, filed on Jul. 20, 2018, now abandoned.

(57) **CLAIM**

The ornamental design for a vaporizer cartridge, as shown and described.

DESCRIPTION

FIG. 1 is a left side, top, and front perspective view of a vaporizer cartridge of our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dash broken lines illustrate portions of the vaporizer cartridge that form no part of the claimed design.

The dash-dot broken lines illustrate boundary lines that form no part of the claimed design.

The oblique lines indicate surfaces of the vaporizer cartridge that are transparent.

1 Claim, 5 Drawing Sheets
